UNITED STATES PATENT OFFICE.

ERNEST W. PITTMAN, OF FLUSHING, NEW YORK, ASSIGNOR TO NEW ENGLAND
WESTINGHOUSE COMPANY, A CORPORATION OF MASSACHUSETTS.

METHOD OF AND MACHINE FOR HARDENING AND STRAIGHTENING RODS.

1,346,419.

Specification of Letters Patent.

Patented July 13, 1920.

Application filed January 5, 1918. Serial No. 210,524.

To all whom it may concern:

Be it known that I, ERNEST W. PITTMAN, a citizen of the United States, and a resident of Flushing, in the county of Queens 5 and State of New York, have invented a new and useful Improvement in Methods of and Machines for Hardening and Straightening Rods, of which the following is a specification.

10 This invention relates to a method of and machine for hardening and straightening rods, particularly gun-cleaning rods.

In practice, one form of gun-cleaning rod is made of a straight piece of steel wire 15 about $\frac{1}{16}$ inches in diameter and 30 inches in length. The specifications for these rods require that they shall be made absolutely straight and shall be so tempered that they will return to their original straight shape 20 after having been bent in an arc of a circle of about 30 inches radius. The object of my invention is to provide a method and machine by which such rods, round bar stock, and similar materials, may be simultaneously straightened and hardened so 25 that they will meet the severe requirements of the specifications. The invention is applicable to tubular structures, and generally to forms generated by the revolution of a 30 surface about an axial line. For convenience, such structures will be hereinafter referred to generally as rods.

In carrying out my invention, the rods are subjected to pressure and rolled over 35 a surface provided with means for quenching the heat at the proper rate to produce the requisite hardening while they are under pressure. To accomplish this, the rolling surface may be covered with the proper 40 amount of oil during the rolling operation because more or less than the proper amount of oil will not produce the results desired. Accordingly, another object of my invention is to provide a machine in which the 45 film of cooling oil on the rolling table is constantly renewed but is kept at substantially a uniform predetermined depth during the rolling operation. Other fluids than oil, and in some instances air or cooling vapors may be used.

50 Another object of my invention is to provide means, in a machine of this character, for preventing one portion of the rod from chilling and buckling before pressure is applied to it by the rolling device.

The above and other objects and the novel features of my invention will be apparent from the following description taken in connection with the drawings that form a part of this invention and in which Figure 1 is a 60 plan view of a machine embodying this invention; Fig. 2 is a side elevation of the same; Fig. 3 is an end elevation of the machine shown in Figs. 1 and 2, the oil tank being shown in section; Fig. 4 is a plan 65 view of the table of the machine; Fig. 5 is an enlarged cross-sectional view of the table, plate and associated parts taken on the line V—V of Fig. 1, part of the cushioning means being broken away; Fig. 6 is a 70 sectional view of the table of the machine taken along the line VI—VI of Fig. 4, and Figs. 7 and 8 are respectively fragmental plan and side elevational views of an arrangement for controlling the flow of a 75 cooling fluid, such as oil or air under pressure, to the rod support.

Referring to the drawings, which show one embodiment of my invention, 10 designates the stationary table of the machine 80 which is carried by standards 11 braced together to form a suitable rigid structure. The table 10 preferably consists of a heavy casting provided with a smooth, hardened top surface. The upper surface of the table 85 is provided with a transversely extending row of recesses 12 that are separated by ribs 13, the top edges of which are flush with the top surface of the table. When the heated rod is first deposited on the table 90 10, it is positioned on the ribs 13 and, since these ribs support the rod at intervals in its length, the tendency of a rod to chill along one side and buckle before pressure is applied to it will be reduced.

95 A drainage passage 14 extends from the bottom of each recess 12 to the under side of the table and a transversely extending series of drainage passages 15 extends from the rolling surface 16 of the table through 100 to the under side thereof. The table 10 is also provided with a transversely extending opening 17 through which the rods are charged into the cooling oil tank 18 after they have been rolled the proper length of 105 time on the surface 16.

110 The rolling plate 20, which co-operates with the table 10, consists of a heavy casting supported on the table 10 by means of pairs of rollers 21, 21', journaled in the

plate 20. The rollers 21 support the rolling surface 22 of the rolling plate spaced from the top surface of the table 10 but the distance between the coöperating surfaces of 5 the table and of the rolling plate being less than the diameter of the rods to be rolled, the rollers at the end of the plate which first engages a rod will be raised and cease to support the weight of that end of the rolling plate, so that this weight will exert pressure on the cleaning rod while it is being rolled over the rolling surface 16 of the table 10.

The rolling plate 20 has a transversely extending elongated slot 23 therein between one end and the pair of rollers 21. This slot extends through the rolling plate 20 from its upper side to the lower side and the longitudinal walls thereof diverge outwardly to form a funnel-shape passage for feeding heated rods into the space 24 and directly upon the ribs 13 of the table 10. When the heated rods are fed upon the table, the outlet end of the slot 23 is directly above the row of recesses 12 and ribs 13. On one side of the slot 23, the lower surface of the rolling plate 20 is inclined upwardly, as at 25, so that, as the plate is moved toward the right, viewing Fig. 5, it will gradually roll upon a rod A supported by the ribs 13 and, thereafter, the adjacent end of the plate 20 will be supported by the rod, moving the latter toward the right and upon the rolling surface 16, as the plate 20 is moved in the same direction.

A suitable cooling and tempering oil is supplied to the rolling surface 16 by a pipe 26 which is supported on the right end of the rolling plate 20 by brackets 27. The 40 pipe 26 is provided with a series of perforations 28, in the lower side thereof which feed the oil continuously to the rolling surface 16, in advance of the plate 20. The pipe 26 is connected to a suitable oil supply by means of a hose connection 29.

Some of the excess oil from the pipe 26 drains from the rolling surface 16, through the opening 17, into the oil tank 18, but, in order to maintain the film of oil on the rolling surface 16 of substantially a predetermined uniform thickness, I employ a wiper 30 of felt or some similar material. The wiper 30 has one edge thereof relatively free and the other end is secured to a wooden block 31 that is resiliently supported by springs 32 in a recess between the block and the end of the rolling plate 20, whereby the springs 32 yieldingly press the wiper 30 against the rolling surface. The wiping device 30 is thus located between the oil-supply pipe 26 and the feed slot 23 so that it will properly distribute the cooling oil on the rolling surface 16 and remove any excess oil therefrom before the rolling plate 20 rolls the cleaning rod on the surface 16.

The wiping device 30 may be so adjusted that it will wipe off only a certain amount of the oil and leave just sufficient oil for properly cooling and tempering the rod. By means of this arrangement, the supply of 70 cooling oil to the surface 16 is constantly being changed, thus keeping the rolling surface sufficiently cold, and, by means of the wiping device, the oil is distributed and the excess oil removed so that only a thin film 75 remains on the rolling surface when a cleaning rod is rolled across it by the rolling plate 20. The excess oil collected by the wiper 30 is discharged through the passages 17 and 15 into the tank below the table.

The mechanism for reciprocating the rolling plate 20 relatively to the table 10 consists of a pair of rocker arms 35 having forked ends to receive pins 36 on opposite sides of the rolling plate. The rocker arms 35 are pivoted, at their lower ends on pins 37 carried by the frame that supports the table. A rocking lever 38 is provided with a handle, at its upper end, is pivoted at its lower end, and is connected by suitable links 39 to the rocker arms 35. It will be obvious that, when the rocking lever 38 is rocked, the rolling plate 20 will be reciprocated back and forth on the table 10. During the rolling operation, the cleaning rod is subjected to the action of the cooling oil while it is held under pressure between the rolling surface 16 of the table 10 and the coöperating surface of the rolling plate 20. After the rolling movement has been repeated several times, the rod is sufficiently chilled to remain straight and the movement of the handle is then continued toward the right until the cleaning rod passes through the opening 17 and is submerged in the oil in the tank 18. The tank 18 contains a large amount of 100 cooling oil that is kept in circulation through a suitable cooling system and from the same system, a portion of the oil is passed into the oil pipe 26. The rolling plate 20 carries a bracket 40 to which one end of a rod 41 is secured. The rod 41 passes through, and extends beyond, a bracket 42 secured to the table 10. The outer end of the rod 41 has a spring retaining washer 43 held in place thereon to which one end of a spiral spring 44 is secured and another spring 45 surrounds the rod 41 on the opposite side of the bracket 42 and is secured to the washer 43. The two springs 105 operate alternately to cushion the movement of the rolling plate 20 when it is moved toward the right and left. The springs together tend to hold the plate 20 in a neutral position.

In Figs. 7 and 8 I have illustrated how another cooling medium such as compressed air may be employed for quenching the rods while they are being rolled. An air pipe 261 provided with outlets 281 and supplied 110

with compressed air from some suitable source, is carried by the plate 201, the parts being arranged similar to the parts 26 and 20 in Figs. 2 and 5. A valve 46 controls the flow of air to the pipe 261 and is normally held to its seat by a stationary cam 47 on the table 101 engaging an antifriction roller 48 on the outer end of the valve stem. The arrangement is such that when the forward end of the rolling plate or carriage 201 is raised by a rod being fed beneath the same, the valve will be opened by the spring 49 and air will be discharged through the openings 281 upon the rolling surface of the table 101.

It will be obvious that power devices may be utilized for operating the rolling plate 20 and that many other changes may be made in the construction and arrangement of the parts of the machine without departing from the spirit of the invention and, therefore, I do not wish to be limited to the exact details shown and described.

I claim as my invention:

1. The method of hardening and straightening rods and the like which comprises rolling the rods under pressure between plane surfaced members and simultaneously treating them with a suitable cooling medium.

2. The method of simultaneously hardening and straightening cleaning rods which comprises subjecting the rods to pressure and rolling them over a plane surface covered with a film of oil while they are under pressure.

3. The method of simultaneously hardening and straightening rods which comprises rolling heated rods under pressure over a surface covered with a film of suitable cooling oil that is constantly renewed and kept at substantially a predetermined depth, and thereafter immersing the rods in cooling oil.

4. In a machine for hardening and straightening rods and the like, the combination with a plane surfaced support for the rods, of means for applying a cooling medium to said support, and means for rolling the rods relatively to said cooled support and simultaneously applying pressure thereto.

5. In a machine for hardening and straightening cleaning rods, the combination with a supporting table for the rods, of means for maintaining a film of oil on the rod-supporting surface of said table, and means for rolling the rods over the oiled surface of the table and simultaneously applying pressure thereto.

6. In a machine for hardening and straightening rods and the like, the combination with a support for the rods, of means for continuously supplying oil to the surface of said support, means for removing excess oil from said surface, and means for roll-

ing the rods relatively to said surface and simultaneously exerting pressure thereon.

7. In a machine for hardening and straightening rods, the combination of a table comprising a supporting surface having a plane portion and a portion provided with means adapted to support a heated rod only at intervals in its length to reduce the tendency of the rod to buckle before pressure is applied thereto, and means for applying pressure to a rod and simultaneously rolling it on the plane portion of the table.

8. In a machine for hardening and straightening rods, the combination with a table comprising a supporting surface having a plane portion and a portion provided with means adapted to support a heated rod only at intervals in its length to reduce the tendency of the rod to buckle before pressure is applied thereto, means for supplying a cooling medium to the surface of the table, means for removing excess cooling medium from the table and means for applying pressure to a rod and simultaneously rolling it on the plane portion of the table.

9. In a machine for hardening and straightening rods, the combination with a table having a transversely extending series of recesses and also provided with drainage passages having their inlets in the bottoms of said recesses and extending through the table, of means for supplying cooling oil to the surface of said table and means for applying pressure to rods on the table and simultaneously rolling them on the oil-covered surface of the table.

10. In a machine for hardening and straightening rods, the combination with a table having a plane supporting surface and a transversely extending opening at one side of said supporting surface, of means for applying pressure to a rod, simultaneously rolling it for a period on said supporting surface, and finally discharging the rod through said opening in the table.

11. In a machine for hardening and straightening rods, the combination with a table, of a rod-rolling plate supported above the table, said plate having a transversely extending slot therein through which rods may be fed into the space between the table and said plate, and means for moving said plate.

12. In a machine for hardening and straightening rods, the combination with a table having a rod-supporting and rolling surface, of a rolling plate supported on the table and having a rolling surface spaced from the rolling and supporting surface of the table, said rolling plate being provided with a transversely extending slot through which a heated rod may be fed into the space between the table and the plate, means for supplying oil to the supporting surface of said table, means for operating said plate,

and means for distributing oil on the table and for removing the excess oil.

13. In a machine for hardening and straightening rods, the combination with a table having a rod-supporting surface, of a rolling plate, means for moving the table and rolling plate relatively to each other, and cushioning means between the table and the plate.

14. In a machine for hardening and straightening rods, the combination with a table having a rod-rolling surface, of a rolling plate having a rolling surface opposed to, but spaced from, the rolling surface of said table, the distance between said rolling surface being less than the diameter of the rod to be rolled but said table and plate being separable to permit the passage of a rod into the space therebetween, means for moving said table and plate relatively to each other, and means for supplying oil to the space between said table and said plate.

15. In a machine for hardening and straightening rods, the combination with a table having a transversely extending series of recesses which are separated by ribs, of a rolling plate mounted above the table and having a rolling surface spaced from the surface of the table, said rolling plate having a transversely extending slot provided with an outlet normally directly above said ribs on the table, means for supplying cooling oil to the rolling surface of said table, means for reciprocating the rolling plate and means, movable by said plate, for distribut-

ing the oil and removing excess oil from the rolling surface of the table.

16. In a machine for hardening and straightening cleaning rods, the combination with a stationary table having a transversely extending row of recesses separated by ribs which are substantially flush with the rolling surface of said table, a rolling plate provided with rollers which support said rolling plate, with its rolling surface spaced from the rolling surface of the table, the distance between said table and said plate being less than the diameter of the rod to be treated, means whereby heated rods may be initially positioned on said ribs so there will be less tendency for the rods to buckle, means for supplying cooling oil to the rolling surface of the table, means for distributing the oil and removing the excess thereof before the rod is rolled onto the rolling surface of said table, and means for reciprocating said plate.

17. In a machine for hardening and straightening rods, the combination with a support, of means for rolling rods on said support, means for applying a cooling medium to said support, and means for controlling the supply of said cooling medium so that it will be applied to said support only during the rolling operation.

In testimony whereof, I have hereunto subscribed my name this fourteenth day of December, 1917.

ERNEST W. PITTMAN.
